UNITED STATES PATENT OFFICE.

FRANK MALOCSSAY, OF NEW YORK, N. Y., ASSIGNOR TO SONORA PHONOGRAPH CORPORATION, A CORPORATION OF NEW YORK.

AUTOMATIC STOP MECHANISM FOR TALKING-MACHINES.

1,277,443.

Specification of Letters Patent.

Patented Sept. 3, 1918.

Application filed December 31, 1914. Serial No. 879,865.

To all whom it may concern:

Be it known that I, FRANK MALOCSSAY, a citizen of the United States, residing in the borough of the Bronx, city, county, and 5 State of New York, have invented a certain new and useful Improvement in Automatic Stop Mechanism for Talking-Machines, of which the following is a specification.

My invention relates to talking machines, 10 and more particularly to that type known as disk record machines.

In talking machines of the disk record type the stylus is caused to engage the record groove by means of the weight of the 15 sound box, and if the turn-table be not stopped when the stylus reaches the end of the record groove, the stylus will cut into the surface of the disk and form a groove which will give off a harsh sound the next 20 time the record is used. The engagement of the stylus with the surface of the disk may also break the stylus point and render the same unsuitable for further use.

The object of my invention is to provide 25 means whereby the movement of the turn-table and record will be automatically arrested when the stylus or reproducer point reaches the end of the record groove.

Another object is to produce such a device 30 which will be simple in construction, economical of manufacture, positive in operation, easily manipulated, and unlikely to get out of order.

These and further objects will more fully 35 appear from the following specification and accompanying drawings considered together or separately.

My invention is illustrated in the accompanying drawings in which similar reference characters designate corresponding parts in all of the figures.

Figure 1 is a plan view of a disk talking machine and cabinet with the cover removed, embodying my invention.

Fig. 2 is a front view of the same with a portion of the cabinet front removed.

Fig. 3 is a plan view of the operative parts of my improved device, the tone-arm being omitted; with the turn-table illustrated in broken lines; the parts being shown in position with the brake shoe removed from engagement with the turn-table.

Fig. 4 is a similar view showing the brake applied.

Fig. 5 is a detail view of a portion of the mechanism.

Fig. 6 is a section on the line 6—6 of Fig. 3; and

Fig. 7 is a detail sectional view of a portion 60 of a record tablet.

In the drawings 1 designates a cabinet which carries the usual motor and sound amplifying device, and having its front panel provided with openings through 65 which the sound may be emitted to the atmosphere. The cabinet is provided with a shelf or partition 2 and cover (not shown). The motor shaft 3 projects through the shelf or partition 2; upon said shaft 3 is 70 mounted a turn-table 4, upon which is supported a record tablet 5 provided with a sinuous record groove. Rotatably mounted on the shelf or partition 2 is a tone-arm 6 of the ordinary type, on the outer end of which 75 is the usual sound box carrying a diaphragm and a stylus or reproducer point of any suitable type.

Secured to the shelf or partition 2 is a bed plate 7, on which most of the operating parts of my invention are supported. The motor shaft 3 projects through the bed plate. Pivoted to the bed plate at 8 is a lever 9. This lever rests upon the plate and is provided with an opening 10 which surrounds the motor shaft and permits the lever to move in relation thereto. Mounted on the lever 9 is a star-wheel 11 and the star-wheel carries a disk 12 on its under surface. The disk 12 is provided with a 80 peripheral cam 13. The star-wheel also carries a second cam 14 which may conveniently be made on the lower face of the cam 12. The free end of the lever is moved in one direction by a spring 15 and a stop 16 85 limits the movement in that direction. The turn-table 4 carries on its under side a roller 17 which is brought into engagement with the star-wheel 11 once in each revolution of the turn-table, and rotates the star-wheel 100 one spoke or, in the embodiment shown, one-fifth of a revolution.

A tumbler 18 is pivoted to the bed plate at 19 and its free end is held in engagement with the cam 13 by means of a spring 105 20, and the said tumbler is provided with a finger 21 near its free end.

A swinging arm 22 is pivoted to the bed plate at 23, and extends toward the tumbler 18 with its free end in proximity to the 110

finger 21. Projections 24—24 are arranged so as to limit the movement of the swinging arm 22. Said swinging arm is provided with a plug 25 of soft material such as felt, leather or rubber, which projects from the under side of the swinging arm; it is also provided with a pin 26 projecting from its under side. A lever 27 is pivoted to the shelf or partition 2 and projects under the swinging arm 22. A spring 28 serves to move the lever 27 in one direction, and a pin 29 limits the movement in that direction. The lever 27 is provided with a notch 30 having inclined sides. The notch 30 is in line with the pin 26, so that when the lever is moved against the tension of its spring the notch will engage the pin and move the swinging arm 22 to its central position. A detent 31 is pivoted to the bed plate and one of its ends engages the lever 27, and its other end is engaged by the cam 14, so that at each revolution of the star-wheel, the lever 27 will be moved against its spring, and the swinging arm 22 will be brought to its central position.

Rigidly secured to the movable part of the tone-arm 6 is an arm 32 provided with a curved foot 33. When the tone-arm is in position to allow the stylus or reproducer 30 point to engage with the record groove on the tablet, the foot 33 is in position under the swinging-arm 22, with the plug 25 resting on the foot, and producing frictional engagement of the foot 33 and the swinging-arm 22. As the foot is moved in coincidence with the travel of the stylus across the face of the record, the swinging-arm 22 will be moved in the same direction until it is halted by one or the other of the projections 24, but at each revolution of the star-wheel the notch 30 will engage the pin 26 and bring the swinging-arm 22 to its central position. When the notch is removed from engagement with the pin the arm 22 will again move away from its central position, and against one of the projections 24. This operation will be repeated as long as the turn-table is rotated with the stylus in engagement with the record groove.

50 When the foot 33 is under the swinging arm 22, it will be held in the same plane as the finger 21. At each revolution of the star-wheel the cam 13 will engage the tumbler 18, and if the swinging arm be held against either of the projections 24 by the movement of the foot 33, the tumbler will be moved. If, however, the foot be at rest, the swinging arm will be in its central position when the cam 13 engages the tumbler 18, and the finger 21 will engage the end of the swinging arm, thereby preventing movement of the tumbler. When this occurs, the cam 13 on engaging the tumbler will move the lever 9 away from the tumbler against the tension of the spring 15.

The swinging arm 22 is loosely carried on its pivot 23, so that when the foot 33 is withdrawn from beneath it the free end of the arm will fall below the plane of the finger 21, so that the turn-table star wheel 11 and 70 cam 13 may be rotated and the tumbler 18 oscillated without moving the lever 9.

Pivoted to the shelf or partition 2 is a brake lever 34 provided with an operating handle and with a brake shoe 35, adapted to 75 be held in engagement with the periphery of the turn-table. A spring 36 normally holds the brake shoe in engagement with the turn-table.

A lock lever 37 is pivoted to the shelf or 80 partition 2 at 38. One end of the lock lever engages the free end of the lever 9, and its other end is adapted to engage the brake lever 34 and hold the brake shoe away from the turn-table. A spring 39 holds the end 85 of the lock lever in engagement with the lever 9.

The record disk or tablet 5 is provided with the usual helical record groove 40, and in addition has a circular groove 41 at the end 90 of the record groove. This groove 41 may be impressed in the face of the disk during manufacture or it may be made with the recording stylus after the record groove is finished.

The record groove being helical feeds the stylus across the face of the disk, and in so doing moves the foot 33 under the arm 22. When the stylus reaches the circular groove 41 the feeding movement ceases, the foot is 100 brought to rest, and the swinging arm 22 is swung to its central position by the engagement of the notch 30 with the pin 26, so as to be engaged by the finger 21 when the tumbler 18 is moved.

I prefer to use two circular grooves 41 impressed in the disk, one on the inside and one on the outside of the space to be occupied by the record groove, for the reason that in some cases the record groove begins at the 11 inside and in others it begins at the outside, and where the circular groove is formed during the manufacture of the disk, they can be made alike, and will answer for either style of record groove.

It will be understood that only one circular groove, at the end of the record groove, is necessary.

It will be further understood that my invention may be carried out without the use of the circular groove for the reason that without such a groove when the stylus reaches the end of the record groove, it will run out of the groove onto the surface of the disk and the feed of the foot will be stopped.

The operation is as follows:

When the record is placed on the turn-table and the motor started, the tone-arm is swung over the record and the foot 33 is brought into position under the swinging-

arm 22 and raises it to the same plane as that of the finger 21; the sound box is now lowered until the stylus rests in the record groove; the rotation of the turn-table will feed the stylus across the record, and the frictional engagement of the foot with the swinging-arm will move the latter in the same direction as that of the stylus. At each revolution of the turn-table the roller 17 will engage the star-wheel and rotate it one spoke. At each revolution of the star-wheel the cam 14 will move the lever 27 and the notch 30 will bring the swinging-arm to its central position. When the cam 14 passes, the lever 27 will swing back and the foot will move the swinging-arm to one side, so that when the cam 13 engages the tumbler 18 the swinging-arm will be to one side of the finger 21 and the tumbler will swing on its pivot and the finger 21 will not engage the end of the arm 22.

When the stylus reaches the end of the record groove it will enter the circular groove, the feed of the stylus will then be arrested, and the foot 33 will come to a standstill, and will no longer influence the swinging-arm 22 except to hold it up in the same plane as that of the finger 21. When the cam 14 moves the lever 27 the notch 30 will center the swinging-arm, and as it is no longer under the influence of the foot, it will remain in that position, and when the cam 13 engages the tumbler 18 it, the tumbler, cannot be moved on account of its engagement with the swinging-arm, and the cam, and with it the lever 9 will be moved away from the tumbler. The end of the lever 9 will engage the lock-lever 37, and move it away from its engagement with the brake-lever, and the spring 36 will apply the brake-shoe and stop the rotation of the turn-table. The parts will now be in the position shown in Fig. 4 and locked in that position by the engagement of the arm 22, the finger 21 and the cam 13.

When it is desired to start the turn-table, the brake-shoe is released from its engagement with the turn-table, which will then be rotated by the motor, the star-wheel will move the cam 13 from engagement with the tumbler 18, the spring 15 will move the lever 9 against the stop 16, and the lever 37 will be moved by the spring 39 to engage the brake-lever and hold the shoe away from the turn-table, which will be permitted to rotate as before.

When the tone-arm is swung clear of the record, the foot is withdrawn from below the arm 22, the latter will drop out of the path of the tumbler, and the turn-table may rotate indefinitely without affecting the brake.

In accordance with the provisions of the patent statute, I have described the principle of my invention together with the appa-

ratus which I now consider to represent the best embodiment thereof, but I desire to have it understood that the apparatus shown is merely illustrative, and that the invention can be carried out in other ways without departing from the spirit of my invention. 70

Having now described my invention what I claim as new and desire to secure by Letters Patent of the United States, is as follows:

1. In a talking machine, the combination with a turn-table, a brake coöperating with the turn-table, means for locking the brake out of contact with the turntable, a record carried by the turn-table, and having a 80 helical record groove, an arm, a stylus, connections between the arm and stylus whereby the movement of the stylus by its engagement with the groove will move the arm in one direction, of means operated by the 85 movement of the turn-table to move the arm in the other direction, and connections between the arm and brake whereby the brake is unlocked when the connections engage the arm. 90

2. In a talking machine, the combination with a turn-table, a brake, means for applying the brake to the turntable, means for locking the brake out of contact with the turntable, a record carried by the turn-table, 95 and having a helical record groove, an arm, a stylus, connections between the arm and stylus whereby the movement of the stylus by its engagement with the groove will move the arm in one direction, of means operated by the movement of the turn-table to move 100 the arm in the other direction, and means operated by the movement of the turn-table to engage the arm and unlock the brake after it has been moved by the last mentioned means. 105

3. In a talking machine, the combination with a turn-table, a brake, a record carried by the turn-table, said record having a helical record groove, an arm, a stylus engaging 110 the record groove, connections between the arm and stylus, whereby the movement of the stylus by its engagement with the groove will move the arm in one direction by frictional engagement with the connection, of a lever engaging the brake lock, a star-wheel carried by the lever, means carried by the turn-table to rotate the star-wheel, a lever for moving the arm relatively to the connection, means carried by the star-wheel for moving the last mentioned lever, a tumbler for engaging the arm, and means carried by the star-wheel for engaging the tumbler to move the star-wheel and its supporting lever away from the arm, and move 120 the lock to release the brake. 125

4. In a talking machine, the combination with a turn-table, and means for rotating the same, a brake, means for applying the brake, means for locking the brake, a 130

the turn-table, said disk having a helical record groove, a stylus for engagement with the groove, a support for the stylus, an element carried by the support, an arm coöperating with the element, of means whereby when the arm is in a predetermined position, the lock will be released, and means whereby when the stylus is removed from the path of the record groove the arm will 10 be removed from the path of the brake releasing means.

12. In a talking machine, the combination with a turn-table, means for rotating the same, and a brake for arresting rotation of 15 the same, a lock for the brake, means for releasing the lock, a record disk carried by the turn-table, said disk having a helical

record groove, a stylus for engagement with the groove, a support for the stylus, an element carried by the support, an arm coöperating with the element, of means whereby when the arm is in a predetermined position, relatively to devices operated by the rotation of the turn-table, the lock will be released, and means whereby when the stylus is removed from the path of the record groove, the arm will be removed from the path of the brake releasing means. 20 25

This specification signed and witnessed this 15th day of December, 1914.

FRANK MALOCSAY.
